C. JOBST

TUFT SEPARATING MECHANISM FOR BRUSH MACHINES

Original Filed April 1, 1924

UNITED STATES PATENT OFFICE.

CONRAD JOBST, OF TOLEDO, OHIO, ASSIGNOR TO THE TOLEDO AUTOMATIC BRUSH MACHINE COMPANY, OF TOLEDO, OHIO, A CORPORATION OF OHIO.

TUFT-SEPARATING MECHANISM FOR BRUSH MACHINES.

Application filed April 1, 1924, Serial No. 703,374. Renewed November 12, 1927.

The invention relates to the manufacture of brushes and has for its object the obtaining of a high rate of production and a high grade product. In the present state of the art various expedients have been employed for separating bristles from the mass and forming tufts. With slow operating machines such separation can be easily performed, but where the machine is operating at a high rate of speed, it is exceedingly difficult to obtain tufts of uniform density. Thus there is danger either of too high compression and the consequent injury to the bristles, or of gathering too few of the bristles and forming a poor tuft. With the present invention the compacting of the bristles to the desired density is secured by their own inertia, while danger of over-compression is avoided by maintaining an unobstructed opening to the measuring pocket through which an over-supply can be freely discharged. Thus the usual picking point is entirely dispensed with and the mechanism is otherwise simplified by dispensing with feeding teeth or equivalent means commonly used.

In the drawings:

Figure 1 is a sectional front elevation of the machine;

Figure 2 is a sectional plan view thereof; Figures 3, 4, 5, 6 and 7 are enlarged diagrams showing the successive position of parts in the separation of the tuft.

The general construction of the machine is similar to constructions that have heretofore been used, comprising a bristle magazine A, preferably flaring or enlarging in diameter in the direction of feed and provided with a spring-pressed follower B for advancing the bristles therein. Near its forward end this magazine is provided with the inclined wall C for contracting the space at the forward end and this wall is periodically oscillated to assist in the downward feeding of the bristles. The tuft separating and transferring means comprises the so-called picking needles D and E which are reciprocated across the forward end of the magazine and are given a substantially harmonic movement. These needles are actuated by slides F and G engaging a guideway H and the slide F is positively actuated by suitable means such as the pin I and bell crank lever J, the latter being driven by a link K from a harmonically reciprocated

part of the tuft driving or setting mechanism. As this tuft setting mechanism forms no part of the present invention, it will not be described in detail.

The slide G which carries the needle E is yieldably driven from the slide F through the medium of the spring-pressed plunger G', but is arrested prior to the completion of the movement of said slide F through an adjustable stop L on the guide H. Thus in operation the needle E is first arrested, after which the needle D continues to move to separate therefrom and to permit of filling the space therebetween with bristles from the magazine.

The mechanism thus far described has been heretofore used, but has had certain objectionable features. Thus it is usual to form the needle D with a sharp point for separating the bristles in the pocket between the needles and the mass in the magazine. Also it is usual to provide a feeding point periodically inserted into the bristles in the magazine and actuated to force the same forward into the pocket between the needles. Such features greatly interfere with the operation of the machine at high velocity and with the present construction are therefore dispensed with. On the other hand, it is equally necessary to obtain an exact measurement of the size of tufts and to form the same of uniform density, which is accomplished as follows:

The needle E is formed with a hooked lower end E' extending perpendicular to the direction of movement. The so-called needle D is a straight bar with a square end parallel to the hook E'. Both needles slide in a bifurcated guide member M, which is adjustably secured to the frame by the screw M' so that the pocket between the needles may be increased or decreased in depth. Adjacent to the needle D is a guide member N which is adjustably secured to the frame by screws N' to permit of accurately setting the same in relation to said needle. The arrangement is such that in normal operation the needle D during its reciprocation is practically in contact with the slide N and acts as a cut-off for separating the bristles, which are in the pocket between the needles from the mass in the magazine.

The successive steps in the operation of forming a tuft are illustrated in the enlarged diagrams and are as follows: As shown in

Figure 3 the needles D and E are ascending, but are in a position with the pocket between the same below the bottom of the magazine. Here the mass of bristles in the magazine is 5 pressed against the edge of the needle D. In Figure 4 the needles are at the point of arrest of the needle E, where the pocket is in open communication with the mass of bristles. In Figure 5 the needle E is in the same 10 position, but the needle D has moved upward to greatly enlarge the opening in the pocket, which as shown is filled by the forward pressing mass of bristles. In Figure 15 6 the needle D has again descended to the position shown in Figure 4 and during its descent has compressed the bristles to the desired density, while the surplus quantity has been forced out into the magazine. In Figure 7 both needles have descended and 20 the needle D is just cutting off communication between the pocket and the magazine. It will be noted that in the position shown in Figure 5 the density of the bristles in the pocket is not uniform and particularly that 25 the bristles at the inner corners of the pocket are lacking in density. However, in the subsequent operation, as shown in Figure 6, the movement of the needle D has compacted the bristles in the pocket and as the opening 30 of the pocket is unobstructed, any surplus quantity is forced rearward into the magazine. Such a mechanism can operate at a rate of speed as high as eight tufts per second, and in each operation will separate a 35 tuft of uniform density and without injury to the bristles.

An important feature of the improvement is the adjustment of the guide N. This is originally set within a fraction of a thousandth from contact with the needle D and whenever, through wear or otherwise, the space between said members is increased, the guide can be quickly reset. The adjustment of the bifurcated guide member M is used 45 for increasing or decreasing the depth of the pocket between the needles and thereby correspondingly increasing or decreasing the size of the tuft. The adjustable stop L permits of varying the position of arrest of the needle E and this is preferably set so as to be a short distance above the bottom of the magazine. Thus the machine may be set to form tufts of any desired size and may be easily maintained in exact adjustment 50 during its operation.

What I claim as my invention is:

1. The combination with a bristle holding magazine and means for yieldably advancing the mass of bristles therein, of a pair of

cooperating needles reciprocating across said magazine, said needles forming therebetween, while in registration with said magazine, an open pocket, and means for moving said needles relative to each other while in registration with the magazine to alternately expand and contract the width of said pocket to successively receive bristles from the mass, compress the same and eject the surplus. 60

2. The combination with a bristle holding magazine and means for yieldably advancing the mass of bristles therein, of a pair of cooperating needles reciprocating across said magazine, said needles having opposed parallel faces forming therebetween, while in registration with said magazine, a pocket in open communication for its full width with said magazine, and means for moving said needles relative to each other while in registration with the magazine to alternately expand and contract the width of said pocket to successively receive bristles from the mass, compress the same and eject the surplus. 70

3. The combination with a bristle holding magazine and means for yieldably advancing the mass of bristles therein, of a pair of cooperating needles reciprocating across said magazine, one of said needles being formed with a square end and the other with a hook providing an opposed surface parallel to said square end, and means for moving said needles relative to each other while in registration with the magazine to alternately expand and contract the space between said parallel surfaces, whereby bristles entering the expanded space under the yielding pressure are compressed to a predetermined density with the ejection of the surplus bristles. 80

4. The combination with a bristle holding magazine and means for yieldably advancing the mass of bristles therein, of a pair of cooperating needles reciprocating across said magazine, one of said needles being provided with a square end and the other with a hook presenting an opposed surface parallel to said square end, a bifurcated guide in which said needles reciprocate, said guide being adjustable to vary the depth of the space between said opposed surfaces, and means for moving said needles relative to each other while in registration with the magazine to alternately expand and contract the width of said space, whereby bristles entering the space when expanded will be compressed and the surplus bristles ejected. 100

In testimony whereof I affix my signature.

CONRAD JOBST.
